CLAIM

I claim the design of a stationary holder for personal electronic communication device (book), as shown and described.

DESCRIPTION

FIG. 1 is a rear perspective view of the stationary holder for personal electronic communication device (book), showing the front cover in the open position;

FIG. 2 is a top plan view thereof, with the top cover open;

FIG. 3 is a rear side view thereof, with the top cover open;

FIG. 4 is a top right side perspective view thereof, with the top cover closed;

FIG. 5 is a bottom plan view with the top cover open;

FIG. 6 is a front side view thereof, with the top cover open;

FIG. 7 is a top left perspective view thereof, with the top cover closed;

FIG. 8 is a rear side view thereof, with the cover closed; and,

FIG. 9 is a rear top view thereof indicating placement of a personal digital assistant (PDA).

The broken line showing of environment in the drawings is included for the purpose of illustrating only and forms no part of the claimed design.
